(57) **CLAIM**

The ornamental design for a light detection and ranging (LIDAR) component, as shown and described.

DESCRIPTION

FIG. 1 is a bottom front perspective view of a LIDAR component;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the LIDAR component that form no part of the claimed design. The dot-dot-dash line shown in the figures represents the bounds of the claimed design.
